UNITED STATES PATENT OFFICE.

HUGO DOTZER, OF SEATTLE, WASHINGTON.

VALVE FOR INTERNAL-COMBUSTION ENGINES.

1,407,644.

Specification of Letters Patent. Patented Feb. 21, 1922.

Application filed November 24, 1919. Serial No. 340,158.

To all whom it may concern:

Be it known that I, Hugo Dotzer, a citizen of the United States, and resident of the city of Seattle, county of King, and 5 State of Washington, have invented certain new and useful Improvements in Valve for Internal-Combustion Engines, of which the following is a specification.

My invention relates to improvements in 10 internal combustion engines, and more particularly to improvements in the construction of cylinder heads and valve mechanism employed in connection with such engines; the principal object of the invention being 15 to simplify and lessen the number of operating parts usually employed in internal combustion engines by a construction wherein in each cylinder is served by a single valve for both its intake and exhaust periods.

20 It is also an object of the invention to provide a construction whereby the usual rocker arms, with their rods and guides, are eliminated by the use of a cam shaft that is common to all and operates directly on the 25 valves.

A further object of the invention is to provide a cylinder head for housing the valve mechanisms, comprising fuel inlet channels located in such manner as to make 30 possible pre-heating of the fuel gases and to provide space for a combustion chamber which is free from pockets or corners that would hold burned or dead gases.

In accomplishing these and other objects 35 of the invention, I have provided improved details of construction, the preferred forms of which are illustrated in the accompanying drawings, wherein—

Fig. 1 is a vertical section of a cylinder 40 head and valve mechanism, constructed in accordance with the present invention, showing the valves in different positions.

Fig. 2 is a horizontal, sectional view of the same, on the line 2—2 in Fig. 1.

Fig. 3 is a vertical section transversely 45 through the cylinder head.

Fig. 4 is a detail side view of the movable valve mechanism.

Fig. 5 is a perspective view of the exterior 50 valve sleeve.

Fig. 6 is a similar view of the interior sleeve.

Fig. 7 is a transverse section of the cam 55 shaft, showing the face view of the cam.

Referring more in detail to the drawings—

1 designates the cylinder head proper, which as shown, accommodates two engine cylinders as indicated in dotted lines in Fig. 1, and to which the head may be attached in the usual or in any other suitable manner. It is to be understood however, that cylinder heads of this character may be adapted to cover not only two, but any desired number of cylinders according to the size or 60 type of engine on which it is to be used.

In the present device the head comprises two valve casings, 2 and 2', which are substantially cylindrical, and open at their inner ends in registration with the cylinders which they accommodate and, at their outer ends, to the upper face of the head; the outer walls of the head forming a jacket within which a cooling medium may be circulated about the valve casings.

Centrally and at one side of the head is an opening 3, with which inlet channels 4 and 4' are directly connected to supply fuel charges to the cylinders through the valve casings, the fuel being delivered to the opening 3 through the usual manifold, not shown, which may be attached to the head.

Located within each of the valve casings is a valve mechanism for controlling the passage of fuel gases into and from the cylinders, and since both valves shown are identical in construction and in operation, but one will be described in detail with the understanding that the description relates equally to both. Each valve mechanism 85 comprises at its upper end, a sort of trunk piston 5, provided in its side wall with a lateral opening 6 which is adapted to register with the inlet channel 4 when the piston is moved to its lower limit, which will 90 allow fuel to be delivered into the cylinder. The piston is also of sufficient length that, except when at its lower limit, it will close the inlet passage as is shown in Fig. 3.

Threaded into the base of the piston and 100 secured by means of a wedge screw is the upper end of a rod 8 which extends downwardly, centrally within the casing and at its lower end is fixed to a valve member 9 of particular construction, consisting of 105 a valve head having an upstanding, peripheral flange 10 provided externally with an upwardly facing, conical face 11 which is

adapted to seat, when the valve is moved to its upper limit, against a downwardly facing conical seat 12 at the lower end of a sleeve 13 that fits snugly within and at its upper end is threaded into an enlargement 15 in the lower portion of the casing.

The flange of the valve is also provided inferiorly with a cylindrical seat 16 which is adapted to snugly receive the lower end of 10 a second sleeve 17, provided at its upper end with a peripheral flange 18 which is also threaded into the enlargement of the casing and is clamped between the upper end of the sleeve 13 and an annular shoulder 14 within the casing. The sleeve 17 has an 15 interior diameter equal to that of the upper end of the casing wherein the piston member is mounted and has an exterior diameter which is sufficiently less than the interior 20 diameter of the sleeve 13 that an annular channel 19 is formed between the two sleeves.

Supported above and from the valve 9 by means of spacing bars 20 is a ring valve 21, which is slidably contained within the annular channel 19. This ring is provided with packing or piston rings as indicated at 22, to prevent leakage between the sleeves.

The exterior sleeve 13 is provided circumferentially with a series of spirally directed 30 openings 25 for providing communication between the channel 19 and an exterior annular passage 26 formed within the enlargement of the valve casing; and which opens into an exhaust passage 27, particularly 35 illustrated in Fig. 3, through which burned charges are exhausted from the cylinder.

The movable valve mechanism is at all 40 times urged upwardly by means of a coiled spring 30 which encloses the rod 8 and at its upper end bears against the inner face of the piston 5, and at its lower end against a spider construction 31 formed within the 45 fixed sleeve 17. This spider also supports a guide bearing 31' wherein the lower end of the rod 8 is slidably contained.

At its upper end the piston 5 is provided with spaced standards 32 between which a roller 33 is mounted; the roller operating in contact with a cam 35, of particular design, which is fixed on a shaft 39 revolvably mounted in anti-friction bearings 40 carried by standards 41 at opposite ends of the head, so that the shaft extends centrally above the cylinders.

55 As is indicated in Fig. 7, during the compression and explosion stroke of the piston, the roller 33 rides upon a surface of the cam which causes no movement of the valve mechanism, and permits it to rest in a position at its upper limit of travel, as shown in Fig. 3, but during the exhaust and intake strokes, the valve mechanism is gradually depressed as the rounded surface 42 which leads up to the point 43 of the cam 60 is moved against the roller.

With the valve mechanism so constructed and assembled, operation of the engine would be as follows:

Assuming that the cam shaft is being driven from, and is rotating at one half the speed of the crank shaft with which the engine pistons, not shown, are connected, by referring to Fig. 7 it will be understood that during the compression stroke of the piston, the cam causes no movement of the valve mechanism and the latter is retained by the pressure of the spring 30 at its upper limit, as is shown in Fig. 3, so that the valve 9 seats tightly against the lower ends of the sleeves 13 and 17 and prevents escape of 80 fuel from the explosion chamber.

At the proper time the compressed charge is ignited by means of a spark plug, which may be mounted within an opening 50 which leads into the explosion chamber just below the 85 valve. There is also no movement of the valve during the explosion stroke of the piston, but as the piston moves upwardly to exhaust the burned fuel charge, the valve mechanism is gradually moved downwardly 90 so that the head 9 moves away from the seat 12, as is shown at the left in Fig. 1, but does not move sufficiently downward to leave the end of the sleeve 17, and the exhaust gases are forced from the cylinder 95 through the channel 19, ports 25 and exhaust channels 26 and 27.

During the following downward movement of the piston the cam continues to depress the valve mechanism and the head 100 9 is moved clear of the sleeve 17. Simultaneously the piston 5 moves downwardly until its opening 6 registers with the inlet channel 4. The ring valve 21 is also moved downwardly with the valve 9 until it closes 105 the annular channel 19 below the openings 25 and communication with the exhaust is thereby cut off; the parts assuming the position as shown at the right in Fig. 1.

Downward movement of the piston creates 110 a suction which causes the fuel to be intaken through the central passage of the valve mechanism until the point of the valve passes from the roller 33 and the valve parts are again moved to closed position by the pressure of spring 30 against the piston 5, which completes one cycle of operation.

To provide for accurate adjustment of the valve mechanism I have mounted the roller 33 upon a central enlargement 34 of a shaft 115 35 which supports the roller between the standards 32. One end of the shaft has an aperture 36 therein, which may register with any one of a series of holes 37 in a hub portion 38 of a supporting standard, so that the 120 shaft may be rotated to adjust the position of the roller and valve parts, and may then be held at such adjustment by projecting a 125 pin through the registering apertures.

It will be noted, by reference to Fig. 2, 130

that gases entering the distributing channels 4 and 4' are directed against a wall which normally is kept hot by the usual heated condition of the water within the head, 5 which causes the fuel charges to be pre-heated before entering the explosion chambers, a circumstance which is very much desired in engines of this character.

I also prefer to enclose the cams and roller 10 mechanism in housings 60 wherein a lubricating fluid may be confined to lubricate the moving parts of the mechanism.

It is apparent that with such a construction, one valve is made to serve for both the 15 intaking and discharging of fuel, and that movable parts, such as rocker arms and levers are eliminated and a head is provided whereto exhaust and intake manifolds may be easily connected in a manner that will 20 simplify and cheapen engine construction.

Having thus described my invention, what I claim as new therein and desire to secure by Letters-Patent is—

1. In combination, a cylinder head having 25 formed therein, an explosion chamber, a valve cylinder opening at its opposite ends respectively to the exterior of the head and into said explosion chamber, an annular valve channel formed about the lower end of 30 said valve cylinder and opening into the explosion chamber, a fuel inlet passage leading into the valve cylinder, a fuel exhaust passage leading from the annular valve channel, a piston valve mounted for reciprocation within the valve cylinder and operable across the said inlet passage to control 35 the inlet of fuel therethrough, a valve head rigidly connected with the said piston and movable therewith over and from the inner 40 end of said valve cylinder and into and from the annular valve channel, an annular valve member rigidly connected with the valve head and operable within the valve channel across

the exhaust passage to close communication to the latter when said valve head is in open 45 position with respect to the valve cylinder and means for actuating the valve mechanism.

2. In combination, a cylinder head having formed therein, an explosion chamber, a valve cylinder opening at its opposite ends respectively to the exterior of the head and into said explosion chamber, an annular valve channel formed about the lower end of said valve cylinder and opening into the explosion chamber, a fuel inlet passage leading into the valve cylinder, a fuel exhaust passage leading from the annular valve channel, a piston valve mounted for reciprocation within the valve cylinder over said fuel inlet 60 passage and having an open inner end and a port in the side wall thereof movable into registration with said fuel inlet passage, a valve head rigidly connected with said piston valve having a peripheral flange thereon; 65 said head being movable downwardly with the piston from the inner end of said valve cylinder to open communication into the explosion chamber when said fuel inlet passage is opened and movable upwardly therewith 70 to first close said cylinder end and on a further movement to move said peripheral flange into said annular channel to close communication between the explosion chamber and the exhaust passage, an annular 75 valve member rigidly connected with the said head and movable within the annular valve channel to opposite sides of the exhaust passage to close communication to the latter from the explosion chamber only when the 80 lower end of the valve cylinder is open, and means engageable with the upper end of the portion valve for actuating the mechanism.

Signed at Seattle, Washington, this 19th day of November, 1919.

HUGO DOTZER.
